Primary Examiner—Cathron C Brooks*Assistant Examiner*—Kevin K Rudzinski(74) *Attorney, Agent, or Firm*—Carter, DeLuca, Farrell & Schmidt, LLP(57) **CLAIM**

The ornamental design for a ceiling lampholder to accept a fluorescent lamp, as shown and described.

DESCRIPTION

FIG. 1 is a side, front perspective view of the ceiling lampholder to accept a fluorescent lamp showing our new design;

FIG. 2 is a right side view thereof, the left side view being a mirror image thereof;

FIG. 3 is a front view thereof;

FIG. 4 is a rear view thereof; and,

FIG. 5 is a bottom side view thereof.

The broken lines shown in FIG. 4 are included for the purpose of illustration and form no part of the claimed design.
